United States Patent Office

Des. 204,002
Patented Mar. 8, 1966

204,002

GOLF PUTTER

Thomas A. Tanis, 9419 W. Elm, Mokena, Ill., and Stanton
M. Swank, 244 Daniels St., Palatine, Ill.

Filed June 17, 1965, Ser. No. 85,785

Term of patent 14 years

(Cl. D34—5)

FIGURE 1 is a front elevational view of a golf putter embodying our new design;

FIGURE 2 is a side elevational view of the golf putter as depicted in FIGURE 1;

FIGURE 3 is a rear elevational view of the golf putter as shown in FIGURES 1 and 2; and

FIGURE 4 is a top plan view of the golf putter.

We claim:

The ornamental design for a golf putter, substantially as shown.
